UNITED STATES PATENT OFFICE.

ALBERT O. GLOCK, OF COLUMBUS, OHIO.

DESIGN FOR A BRACKET FOR SOAP, &c.

SPECIFICATION forming part of Design No. 26,928, dated April 20, 1897.

Application filed March 5, 1897. Serial No. 626,144. Term of patent 7 years.

To all whom it may concern:

Be it known that I, ALBERTO. GLOCK, a citizen of the United States, residing at Columbus, in the county of Franklin and State of Ohio, have invented a certain new and original Design for Brackets for the Support of Soap and other Articles, of which the following is a specification.

Figure 1 is a view in perspective of the bracket containing my design; and Fig. 2 is an end elevation thereof, the drinking-glass support being omitted therefrom.

The leading feature of my design consists of a back plate, with which is formed a central forwardly-projecting receptacle, and with which is also formed laterally and forwardly extending arms, one of said arms supporting a drinking-glass socket or cup and the remaining arm supporting a vertical standard on which are arranged separated disks, the latter having formed therein, respectively, openings and depressions.

a represents the body or backing-plate of my newly-designed bracket, with which is formed integrally a downwardly and thence

forwardly extending soap cup or receptacle b, the latter preferably being formed with converging scallops b'. With the upper portion of the backing-plate a are formed laterally and forwardly extending arms c and c'. The arm c supports a socket or cup body d, which is preferably formed of open-work. The arm c' supports a tooth-brush stand consisting of a standard e, on the upper end of which is mounted a horizontal disk e' and at the base of which is mounted a second horizontal disk e². The upper disk e' is provided with radially-arranged openings f about its center, while the lower disk e² is provided at points vertically opposite said openings f with suitable depressions g.

I claim—

The design for a combination bracket for the support of soap and other articles, substantially as herein shown and described.

ALBERT O. GLOCK.

In presence of—

C. C. SHEPHERD,
P. S. KARSHNER.
